TEST TUBE RACK

Lisbeth Parker, 146 W. Princeton Ave.,
Youngstown, Ohio 44507

Filed Oct. 7, 1966, Ser. No. 4,224

Term of patent 14 years

(Cl. D16—1)

FIGURE 1 is a perspective view of a test tube rack, showing the top front and one end thereof.

FIGURE 2 is a cross-section on line 2—2 of FIGURE 1. The back and the end not shown are plain.

I claim:

The ornamental design for a test tube rack, as shown and described.
